UNITED STATES PATENT OFFICE.

EUGÈNE MOULIÉ, OF JACKSONVILLE, FLORIDA.

POLLEN-COLLECTING DEVICE.

No. 834,746.

Specification of Letters Patent.

Patented Oct. 30, 1906.

Application filed June 12, 1906. Serial No. 321,325.

To all whom it may concern:

Be it known that I, EUGÈNE MOULIÉ, a citizen of the United States, and a resident of Jacksonville, in the county of Duval and State of Florida, have invented a new and Improved Pollen-Collecting Device, of which the following is a full, clear, and exact description.

This invention relates to pollen-collecting devices by means of which pollen is collected for use in the manufacture of medicines and the like, and is particularly useful in connection with devices of this character in which severed twigs or branches bearing blossoms from which the pollen is to be collected are held with their stems immersed in water or other liquid contained in a vessel.

A further object of the invention is to provide a pollen-collecting device which may be easily moved about from place to place and in which the twigs or branches are retained comparatively secure against accidental displacement.

The invention consists in the construction and combination of parts to be more fully described hereinafter and particularly pointed out in the claims.

Reference is to be had to the accompanying drawings, forming a part of this specification, in which similar characters of reference indicate corresponding parts in all the figures.

Figure 1 is a transverse cross-section of the device in use. Fig. 2 is a similar longitudinal cross-section, and Fig. 3 is a plan view, of my invention.

Referring more particularly to the drawings, I provide a vessel or tank 1, which may be of any suitable shape, but is preferably rectangular in form, as shown in Figs. 1 and 2. The vessel may be made of sheet metal or other suitable material and is provided at the ends with handles 2, loosely mounted in sockets 3, rigidly secured to the sides. By means of these handles the device may be easily moved from place to place as circumstances require. Near the bottom of the vessel and on one of the sides I provide a small tube 4, communicating with the interior, by means of which the vessel may be emptied of the water or other fluid within it when so desired by simply allowing the water to flow out through the tube or through a hose attached to the tube. The tube may be closed ordinarily by inserting a cork or plug 5 in the

end thereof. It will be understood that if so desired this tube 4 may be replaced by a faucet or turn-cock.

Across the open top of the vessel I provide a pair of transverse bars 6 and a pair of longitudinal bars 7, crossing the transverse bars 6 at substantially right angles. The bars are secured to the edges of the vessel by having their extremities bent over these edges and soldered or otherwise rigidly attached thereto. The bars are located across the top of the vessel parallel, respectively, to the sides and longitudinal edges and at a small distance from the same, as shown most clearly in Fig. 3. Mounted upon the cross-bars is a top 8, of sheet metal or other suitable material, the edges of which are bent around the bars and soldered or otherwise suitably secured thereto. The top 8 does not extend to the edges of the vessel 1, but leaves lateral openings 9 between these edges and the top. The top is provided with an opening 10 substantially in the center, which may be of any suitable form, but is preferably rectangular, as shown most clearly in Fig. 3. This opening is formed by making two substantially parallel transverse cuts in the sheet metal comprising the top and a longitudinal cut joining the two transverse cuts. The flaps 11 of the metal thus separated on three sides are then bent downward, as shown most clearly in Fig. 1.

When it is desired to use this device for collecting the pollen from plants, twigs or branches 13 of these plants are severed and are then inserted through the lateral openings 9 with their stems extending into the vessel in a diagonally-downward direction, as shown most clearly in Fig. 1, said stems being immersed in the liquid, preferably water, with which the vessel is filled. The device is placed upon a sheet of paper 12 or other material and is located in a closed room in which the temperature is maintained constantly at a suitable point and from which drafts are excluded, which would be liable to disturb the pollen or blow it away. As the ends of the twigs or branches project beyond the sides of the vessel and extend over the paper upon which the device is placed, the pollen 14 as it separates from the blossoms will fall upon this paper, from which it is easily collected from time to time. As the stems of the twigs are immersed in water, the blossoms

will remain fresh and will gradually ripen under the favorable circumstances of moisture and constant proper temperature.

The downwardly-projecting flaps 11 are useful in holding the twigs 13 submerged and preventing their accidental displacement. It is of advantage to change the water or other liquid in the vessel from time to time, and this may be done without disturbing the plants by withdrawing the liquid through the tube 4 and replacing it with fresh liquid by filling the vessel through the opening 10, and thus in no way disturbing the twigs or branches.

Having thus described my invention, I claim as new and desire to secure by Letters Patent—

1. A device of the class described, comprising a vessel adapted to contain a liquid and having means for holding a plurality of twigs and the like near the edges of said vessel in an inclined position with the stems immersed in the liquid, and a top having an opening whereby the vessel may be filled with liquid.

2. A device of the class described, comprising a vessel adapted to contain a liquid, a top on said vessel, and openings between said top and said vessel, adapted to allow the insertion of twigs and the like, said top having an opening whereby the vessel may be filled with a liquid.

3. A device of the class described, comprising a vessel adapted to contain a liquid, a top extending toward the sides of said vessel and having lateral projections adapted to engage with the edges of said vessel to hold

said top in place, and openings between said top and said vessel adapted to allow the insertion of twigs and the like, said top having 40 an opening whereby the vessel may be filled with a liquid.

4. A device of the class described, comprising a vessel adapted to contain a liquid, cross-bars secured to the edges of said vessel 45 and extending across the same, a top mounted on said cross-bars, openings between said top and the edges of said vessel adapted to allow the insertion of twigs and the like in a diagonally-downward direction, and an opening in said top whereby said vessel may be filled with a liquid.

5. A device of the class described, comprising a vessel, cross-bars secured to the edges of said vessel and extending across the 55 same substantially parallel to the edges thereof, a top mounted upon said bars, and openings between said top and the edges of said vessel adapted to allow the insertion of twigs and the like with the tops thereof extending 60 beyond the sides of said vessel, said top having an opening whereby said vessel may be filled with a liquid, said opening having edges disposed downwardly to act as guards to retain the stems of said twigs immersed in the 65 liquid.

In testimony whereof I have signed my name to this specification in the presence of two subscribing witnesses.

EUGÈNE MOULIÉ.
